UNITED STATES PATENT OFFICE.

ROBERT LEE COONEY, OF ATLANTA, GEORGIA.

STATIONARY FIRE-EXTINGUISHER SYSTEM.

1,075,020.

Specification of Letters Patent.

Patented Oct. 7, 1913.

Application filed June 15, 1910. Serial No. 567,050.

To all whom it may concern:

Be it known that I, ROBERT L. COONEY, a citizen of the United States, residing at Atlanta, in the county of Fulton and State 5 of Georgia, have invented new and useful Improvements in Stationary Fire-Extinguisher Systems, of which the following is a specification.

The present invention is an improvement 10 in stationary fire extinguisher systems and it involves certain novel features of my construction, arrangement and operation, con- 15 ducing to reliability, quickness, certainty and sensitiveness of action in an organized struc- 20 ture which is of simple and inexpensive na- ture.

An embodiment of the invention is illus- 25 trated in the accompanying drawing wherein the figure is a detail longitudinal sec- 30 tional view.

Similar characters of reference designate 35 corresponding parts.

The invention is illustrated in its appli- 40 cation to a dry-pipe system of a type of 45 which I am the originator and which, forming the bases of co-pending applications, Serial Numbers 540,661 and 530,470, need only be described in a general way. In the example illustrated, the system includes a sta- 50 tionary chemical mixing tank, as 1, containing an acid bottle, as 2, and a distributing pipe, as 3, which leads from the tank and has an extension, as 4, which projects there- 55 into. The tank is partially filled with an alkaline solution and the bottle 2 is mount- 60 ed for inverting movement, being pivoted off center upon a bracket 5.

With the mode of operation described in 65 the applications aforesaid it is essential to 70 provide for the maintenance of the pres- 75 sures at equal degrees and for this purpose the pressures are normally in communica- 80 tion through a by-pass pipe, as 6, which may have a capillary bore or which may be, 85 as shown, provided with a diaphragm 7, having an aperture of "pin-hole" diameter.

The extension 4 and the pipe 3 are con- 90 structed to afford an enlarged chamber, as 95 8, which is preferably located above the so- lution level and which incloses a ball, as 9. The latter is, in effect, a valve, and nor- 100 mally closes the mouth of the extension 4 which communicates with the chamber 8. The ball 9 is weighted to some extent for a 105 purpose which will presently appear and is prevented from closing against the end of

the pipe 3, in communication with the cham- 110 ber 8, by a perforated web, as 10, which bridges said chamber.

At one side of the chamber 8, a float cham- 120 ber, as 11, is provided. The upper end of the chamber 11 is open and in communica- 125 tion with the tank. The lower end of the chamber 11 is provided with an opening, as 13, having its wall formed as a valve seat 140 and in communication with a passage, as 13, afforded by a connection which extends 145 downwardly from the chamber 8 to the chamber 11. Within the chamber 11 is a float, as 14, having at its lower end a valve 150 boss 15, which, in the operation of the sys- 155 tem, closes against the wall of the opening 16. The float 14 surrounds an axially dis- 160 posed guide stem, as 14^a and is held in a 165 normal position by a body of liquid, as 16, 170 which partially fills the chambers 8 and 11 175 and which is shiftable consequent to the 180 pneumatic impulse aforesaid but which is 185 naturally at rest in its normal position. 190 This body of liquid is the equivalent of a 195 mechanical element and is to be so consid- 200 ered. The movement of the float 14 is con- 205 sequent to the shifting of the body of liquid 210 16 and the operation of the system is di- 215 rectly consequent to the movement of the 220 float. An advantageous means for effectuat- 225 ing this result consists of a lever 17, which 230 is pivoted between its ends on a bracket 18 235 and which has one end pivotally associated 240 with the float and its other end in latching 245 engagement with a lug, as 19, which is pro- 250 vided at one side of the acid bottle.

From the foregoing description it will be 255 readily apparent that when the body of liq- 260 uid 16 is shifted so that its level in the cham- 265 ber 8 is lowered, the float 14 will descend 270 and in such movement will rock the lever 17 275 and release the acid bottle 2. The latter 280 thereupon inverts and discharges its 285 contents into the body of solution. The de- 290 veloped high pressure forces the solution 295 from the tank and of course produces the 300 displacement of the ball 9 and also acts on 305 the float to cause the valve boss 15 to seal the 310 opening 12, in order that there may be no 315 appreciable escape of pressure therethrough 320 in advance of the out-going column of liq- 325 uid. The organization is of such nature 330 that the operation may be produced with an 335 impulse of exceedingly light character and 340 insufficient to produce the displacement of 345 the ball 9 through the intermediary of the

intervening body of solution. The organization is furthermore of such nature that it is highly sensitive and quickly, practically instantly, responsive to the pneumatic impulse but, when set for operation, will not be disturbed except by a pneumatic impulse which is so developed and transmitted as to provide a motive force.

No specific description herein contained 10 is intended to put any limitation upon the scope of the succeeding claims, which does not inhere in the language thereof.

Having fully described my invention, I claim:

15 1. A stationary dry-pipe fire extinguisher system comprising a tank, a distributing pipe communicating therewith, the tank containing a body of liquid which is shiftable by a pneumatic impulse, a mechanical element which is movable to provide for the 20 supplying of a fire extinguisher agent to the distributing pipe, a float supported by the body of liquid and operatively movable consequent to the shifting of the latter and a latch normally engaging the mechanical element and operatively connected to the float whereby the descent of the latter causes the disengagement of the latch.

2. A stationary dry-pipe fire extinguisher 30 system comprising a tank, a distributing pipe communicating therewith, the tank containing a body of liquid which extends into the distributing pipe and is shiftable by a pneumatic impulse, a mechanical element which is movable to provide for the supplying 35 of a fire extinguisher agent to the distributing pipe, a float supported by the body of liquid and operatively movable consequent to the shifting of the latter and a latch normally engaging the mechanical element and operatively connected to the float whereby the descent of the latter causes the disengagement of the latch.

3. A stationary dry-pipe chemical mixing 45 fire extinguisher system comprising a tank, a distributing pipe communicating therewith, the tank containing an alkaline solution, a chamber in the tank which contains a body of liquid shiftable by a pneumatic impulse and is in communication at its lower 50 end with said distributing pipe, an acid bottle, and mechanism operable consequent to the shifting of the body of liquid in the chamber to produce the discharging operation of the acid bottle.

4. A stationary dry-pipe chemical mixing fire extinguisher system comprising a tank, a distributing pipe communicating therewith, the tank containing an alkaline solution, a chamber in the tank which communicates with the distributing pipe and also with the tank, the chamber containing a body of liquid shiftable by a pneumatic impulse, an acid bottle, and mechanism operable consequent to the shifting of the body

of liquid in the chamber, to produce the discharging operation of the acid bottle.

5. A stationary dry-pipe chemical mixing fire extinguisher system comprising a tank, a distributing pipe communicating therewith, the tank containing an alkaline solution, a chamber in the tank which communicates with the distributing pipe and also with the tank, the chamber containing a body of liquid shiftable by a pneumatic impulse, an invertible acid bottle, a float supported by the body of liquid in the chamber and movable consequent to the shifting of said body of liquid and a latch lever operatively connected to the float and normally 75 engaging the acid bottle to prevent the inverting movement of the latter.

6. A stationary dry-pipe chemical mixing fire extinguisher system comprising a tank, a distributing pipe communicating therewith and having an extension in the tank, a valve chamber interposed between the distributing pipe and the extension, a weighted valve in the chamber and which normally 80 closes the end of the extension, a second 85 chamber adjacent the valve chamber, a connection between the chambers, the latter containing a body of liquid shiftable by a pneumatic impulse, the tank containing an alkaline solution, an acid bottle, and mechanism 90 operable consequent to the shifting of the body of liquid in the chambers to produce the discharging operation of the acid bottle.

7. A stationary dry-pipe chemical mixing fire extinguisher system comprising a tank, a distributing pipe communicating therewith and having an extension in the tank, a valve chamber interposed between the distributing pipe and the extension, a weighted valve in the chamber and which normally 100 closes the end of the extension, a second chamber adjacent the valve chamber, a connection between the chambers, the latter containing a body of liquid shiftable by a pneumatic impulse, the tank containing an alkaline solution, the second chamber having an opening communicating with the connection, a float in the second chamber and having a valve boss to close the opening, the float being supported by the body of liquid and 110 movable consequent to the shifting of said body, an invertible acid bottle, and a latch lever operatively connected to the float and normally 115 engaging the acid bottle to prevent the inverting movement of the latter.

8. A stationary dry-pipe chemical mixing fire extinguisher system comprising a tank, a distributing pipe communicating therewith, the tank containing solution, a chamber in the tank and in communication therewith, a connection between the chamber and the distributing pipe, the chamber having an opening communicating with the connection and containing a body of liquid shiftable by a pneumatic impulse, a float sup- 120 130

ported by the body of liquid and having a valve boss to close the opening in the lowermost position of the float, an invertible acid bottle and a latch lever operatively connected to the float and normally engaging the acid bottle to prevent the overturning thereof.

9. A stationary dry-pipe chemical mixing fire extinguisher system comprising a tank, a distributing pipe communicating therewith and having an extension in the tank, a weighted normally closed valve interposed in the extension, a chamber communicating with the distributing pipe above the valve, the chamber containing a body of liquid shiftable by a pneumatic impulse, an acid bottle and mechanism operable consequent to the shifting of the body of liquid to produce the discharging operation of the acid bottle, the tank containing an alkaline solution, into which the acid bottle discharges.

In testimony whereof I have hereunto set my hand in presence of two subscribing witnesses.

ROBERT LEE COONEY.
